LISTING MECHANISM FOR ADDRESSING MACHINES

Carl J. Hueber, Cleveland Heights, Ohio, assignor, by mesne assignments, to Addressograph-Multigraph Corporation, Cleveland, Ohio, a corporation of Delaware

Application February 25, 1936, Serial No. 65,596

28 Claims. (Cl. 101—47)

This invention relates to a printing machine, and especially to a sheet feeding and listing mechanism therefor, to enable lists to be made from a series of printing devices.

5 The general object of the present invention is to provide a printing machine with a listing mechanism or sheet feeding device, particularly arranged to permit lists to be made from work-sheets of a comparatively large size.

10 A further object is to provide a printing machine of the type having an overhanging platen arm supported on a frame table, with a work sheet feeding device particularly arranged to permit lists and the like to be made on work 15 sheets of such size that ordinarily listing thereon would be prevented by interference with the overhanging platen arm.

15 A more specific object of the present invention is to provide a series printing machine, such as an addressing machine, with a listing mechanism to automatically feed a worksheet to enable 20 impressions to be made thereon in list formations, and to so handle the impressed area of the sheet as to permit comparatively large worksheets 25 to be retained in close proximity to the printing mechanism without interfering with the feeding of the sheet and without damaging the sheet by folds, creases or the like.

20 I prefer to accomplish the object of this invention by providing a sheet feeding or listing mechanism to automatically feed a sheet to a series 30 printing machine and which mechanism will automatically roll or wind up the printed sheet consequent upon the operation of the printing 35 mechanism.

30 Other objects of the present invention will become more apparent from the following description, reference being had to a preferred form of the invention, illustrated in the accompanying 40 drawings. The novel features of the invention will be set forth in the claims.

35 In the drawings, Fig. 1 is a plan view of a printing machine and listing device provided with my improved sheet feed; Fig. 2 is a longitudinal section indicated by the line 2—2 on Fig. 1; Fig. 3 is a fragmentary side elevation of the machine and listing mechanism looking at the right-hand side of the mechanism as viewed in Fig. 1; Fig. 4 is a fragmentary side elevation, similar to Fig. 3, 50 but illustrating certain parts in different operating positions; Fig. 5 is a fragmentary sectional view on a greatly enlarged scale, the plane of the sections being indicated by the line 5—5 on Fig. 1; Fig. 6 is a transverse section, as indicated by the line 6—6 on Figs. 1 and 5, the scale

5 of the section being the same as that of Fig. 5; Fig. 7 is a sectional detail, the plane of the section being indicated by the line 7—7 on Fig. 6; Fig. 8 is a sectional detail, on the same scale as Figs. 5, 6 and 7, the plane of the section being indicated by the line 8—8 on Fig. 1; Fig. 9 is a perspective view illustrating the sheet feeding table and roller mechanism, removed from the machine; Fig. 10 is a sectional detail, as indicated by the line 10—10 on Fig. 9; Fig. 11 is a substantially horizontal section, as indicated by the line 11—11 on Fig. 10.

10 In the drawings, I have illustrated my improved printing mechanism in connection with an addressing machine of the type shown and described 15 in my prior application for Letters Patent, Serial No. 62,416, filed February 5th, 1936, and assigned to my assignee, Addressograph Company. As illustrated in Figs. 1 and 2, such a machine comprises a main frame 10, provided with the horizontal guideway 11, along which printing devices such as address plates D are progressed, 20 one after another, from the bottom of a stack indicated at 12 to an anvil 13 and thence to a second stack 18.

25 A suitable conveyor, such as a pair of reciprocating feed bars 14, is provided to progress the printing devices from one stack to another. The feed bars are reciprocated by an eccentric 15, which is connected by links and levers 16, with the 30 feed bars. The eccentric 15 is secured to a shaft 22 journaled in the frame 10 and rotated by a motor M.

35 When the feed bars 14 move to the right, from the position shown in Fig. 1, suitable abutments 35 19 thereon engage the bottommost printing device in the stack 12 and shove it towards the anvil 13, the same operation causing all devices in the guideway 11 to be moved, by suitable spring-pressed pawls 17, carried by the feed bars. In 40 this manner the printing devices come, one after another, to rest in printing position, namely, on the anvil 13.

45 The platen illustrated is of the roller type and is supported by a pair of spaced frame brackets 45 20. These brackets or arms extend from frame 10 upwardly, forming the magazine 12 at the rear of the guideway 11, and then extend forwardly above and parallel with the guideway. The brackets are spaced apart a distance substantially equal to the length of the printing 50 devices, and are each provided with an inwardly facing guide rail 21, along which the platen mechanism is reciprocated.

55 A more complete description of the platen

- and its operating mechanism is given in my co-pending application for Letters Patent, Serial No. 63,575, filed February 12, 1936, and assigned to my assignee, Addressograph Company. Briefly, 5 the platen mechanism comprises a carriage 25, which is slidably mounted on the guideways 21 carried by the platen arms 20 in such a manner that the carriage is supported between such arms. Mounted in the carriage 25 are a pair of shafts 10 30 and 31, which support a toggle mechanism comprising two pairs of links (one pair of which is shown at 32, 33 in Fig. 2). Each link 32 is pivotally connected to the shaft 30 and to its respective link 33. Each link 33 is in turn pivotally connected, as illustrated in Fig. 2 to a platen shaft 34, which rotatably supports the platen 35. A third pair of links 38 guides the movement of the platen. Each of these links is pivotally connected between the platen shaft 34 15 and the shaft 31, heretofore mentioned. Any means, such as a suitable spring (not shown) may serve to maintain the platen normally in the position shown in Fig. 2. However, when the platen approaches the right-hand end 20 of the brackets 20 (Fig. 2) a roller 36, carried by the pivotal connection between the links 32 and 33, engages an abutment 37, formed on a bracket 20, preventing subsequent movement of the pivot, whereupon continued forward movement of the 25 carriage causes the links 32 and 33 to be aligned, both links extending downwardly from the shaft 30, whereby the platen is moved into engagement with a worksheet W superimposed above the printing device, carried by the anvil 13. 30 Following the engagement of the sheet by the platen, the platen carriage is drawn to the rear (to the left in Fig. 2), causing the platen 35 to be rolled across the printing device supported on the anvil 13. A suitable inked ribbon R disposed between such device and the worksheet causes an impression to follow. When the platen approaches the rear or left-hand limit of its stroke (Fig. 1) an abutment, similar to that shown at 37, may be employed to engage the roller 36, 35 whereupon continued rearward movement of the carriage will cause the links to return to the position illustrated in Fig. 2. The platen carriage may be reciprocated by any suitable means. I have shown, however, in 40 Fig. 2, an eccentric 40, which is connected to a rock arm 41, by a suitable connecting rod 42. The rock arm 41 is rigidly secured at one end to a shaft 43, journaled in the frame, and its other end is connected by a link 44 with the platen carriage. 45 It will thus be seen from the foregoing description that consequent upon the rotation of the shaft 22, to which the eccentrics 15 and 40 are secured, the printing machine will operate to 50 make successive impressions from the successive printing devices on a worksheet W. The present invention comprises a listing device for handling the worksheet W, so that lists, such as a list of names, addresses or the like, 55 may be impressed on the paper, one below the other, in columnar formation, on worksheets of lengths considerably greater than the distance from the anvil 13 to the vertical extending portions 23 of the platen-supporting brackets. 60 As shown in Figs. 1 and 2, the listing mechanism, which forms the subject of this application, comprises, in general, a work table, or guide, 65 56, arranged to be secured in position on the top of the frame 10, and provided with a takeup roller 60 or other means by which the work sheet is

coiled or rolled, following each impression made thereon, as will be hereinafter more fully described. The table 56 extends, as indicated, from a point located forwardly of the anvil 13, (the right in Fig. 2), to a point adjacent the columnar 5 supports 23 of the brackets 20.

The worksheet is initially positioned with its foremost edge between a pair of feed rollers 70 and 71, located intermediate the anvil and the roller 60 at one side of the guideway 11. These 10 feed rolls serve to progress the sheet W from the anvil to the roller 60. It will be noted from Figs. 9 and 10, that the work-supporting plate 50 nearly encircles the roller 60, being formed at its rearmost edge with the tubular portion 51 extending above the plane of the plate and arranged to enclose the cylinder or roller 60. The internal 15 diameter of the tubular portion 51 is somewhat greater than the external diameter of the roller, so that the worksheet may be wrapped around the 20 roller a number of times without binding between the roller and the tube.

The operation of my improved paper feed or lister mechanism is as follows:

The operator positions the worksheet on the 25 table 56 so that its forward edge is gripped by the feed rollers 70 and 71, whereupon the printing mechanism, comprising the plate feed and platen operating devices, heretofore described, is set in 30 operation, causing an impression to be made on the worksheet from the printing device resting on the anvil 13.

Following the making of such impression, the platen is raised clear of the work, the printing devices are advanced to position the next succeeding device on the anvil; the feed rollers 70 and 71 are operated to cause the worksheet to advance to position a fresh portion thereof above the anvil. A second impression is then made, the platen returned and the paper advanced and 40 so on.

As the worksheet W is advanced by the feed rolls 70 and 71, it is guided into the bite between the small rollers 61 and the roller 60, the latter, as will hereinafter be described, being rotated in 45 timed relationship with the movement of the feed rolls, so that the impressed sheet is periodically advanced, and wrapped about the roller 60.

When the last impression desired on the sheet has been made, the operator stops the operation 50 of the printing mechanism, separates the rolls 70 and 71, and at the same time disconnects the roll 60 from its driving mechanism, whereupon the sheet may be readily drawn forwardly from the roll 60 and a new sheet inserted between the feed rolls, whereupon the operation may again be repeated. 55

After a sheet has been withdrawn, a second column may be impressed thereon by moving the sheet either to the right or the left, a distance 60 equivalent to the desired spacing of the columns, whereupon the sheet may again be progressed through the mechanism and a second column of addresses or other subject matter impressed thereon. 65

The feed rolls and the take-up roll are driven from the shaft 43 to which the platen-operating arm 41 is secured, as heretofore described. In Fig. 1, I have shown an arm 80, as drivingly connected to the shaft 43, so that consequent upon 70 the rotation of the eccentric 40, the arm will be oscillated. Removably pivoted to the arm 80 by a suitable pin 81 is a link 82, also pivotally connected as at 83 with a lever 84, pivoted as at 85 to a bracket 86. The lever 84 is, as shown in Fig. 75

5, connected by a link 88 with one leg 87 of a U shaped lever 99, such leg being pivoted as at 89, to the bracket 86. The other leg 91 of the U shaped lever is provided with a slideway 93, which 5 slidably supports a link 92. This link 92 has a pivot pin 90 which extends through a suitable slot in leg 91 of the lever 99 and is secured to a block 98 which is adjustably secured to the lever 99 by an adjusting screw 109.

10 By changing the relation of the pivot pin 90 to the pivot 89 of the lever 99 the stroke of this lever mechanism may be adjusted as desired. The link 92 is also pivotally connected, as at 94, with a crank 95, mounted on a shaft 96, carried 15 by the bracket 86. Mounted on the rock shaft and drivingly connected to the crank 95, is a segmental gear 97, which, as shown in Figs. 3 and 4, meshes with a pinion 100, rigidly secured to the driven member 101 of a suitable uni-directional 20 clutch carried by a shaft 102 journalled in the frame bracket 86. The driving member 103 of this clutch is secured to the shaft 102, so that consequent upon the oscillation of the segmental gear 97, the shaft 102 will be periodically turned 25 in one direction.

The feed roller 70 is drivingly secured to the left-hand end (Fig. 6) of the shaft 102. Immediately below the shaft 102 I provide a second shaft 104, which is journalled to the frame bracket 86 30 and drivingly carries the feed roller 71 which lies beneath the worksheet W, and coacts with the roller 70 to grip and feed the sheet. A pinion 105, drivingly carried by the shaft 104, meshes with a gear 106 drivingly secured to the shaft 102. Hence, the rollers 70 and 71 will be rotated 35 in unison.

The rotative movement of the shaft 102, as heretofore described, results from the movement of the shaft 43 which is operated by the platen-operating eccentric 40. It therefore follows that 40 the paper feed rollers 70 and 71 will be periodically driven in timed relationship to the operation of the address printing mechanism heretofore described.

45 As heretofore mentioned, to insert a sheet between the feed rollers 70 and 71, I prefer to separate the rollers. For this purpose I undercut the shaft 102 as at 27, for considerable length, reducing the diameter of the shaft to such an extent that the shaft becomes somewhat flexible. The 50 left-hand end of the shaft is mounted in a bearing 107, which is mounted for vertical movement in a slideway 108 of the bracket 86. A leaf spring 109 bears against the top of the bearing member 107, and acts to maintain the roller 70 normally 55 in engagement with the roller 71.

To raise the roller 70 clear of the roller 71 I provide a rock shaft 110, the left-hand end of which, as shown in Fig. 6, has a cam surface 111, 60 arranged to engage a face 112 of the bearing member 107, and so arranged that consequent upon the swinging of a shaft 110, by a manually operable lever 113, secured thereto, the bearing member 107 will be raised upwardly, separating 65 the rollers 70 and 71.

To enable suitable positioning of the sheet after it has been gripped between the rollers, consequent upon the release of the operating lever 113, I prefer to provide the right-hand end 70 of the shaft 102 with a knurled knob 114, which may be grasped by the operator to rotate the shaft independent of its operating mechanism. The uni-directional clutch 101, 103 being of the roller type, having its driven member loose on the shaft, this movement of the shaft 102 is readily 75

accomplished without affecting the operating mechanism and without disturbing the timed relationship between the shaft and its driving mechanism.

The take-up roller 60, upon which the sheets 5 are rolled during the printing action, permitting the printing mechanism to utilize a comparatively long sheet without interference of the sheet by the various members of the printing mechanism, is periodically driven and in timed relationship with the feed rolls 70 and 71. As illustrated in Figs. 1, 5 and 8, the roller 60 is provided with a suitable friction surface 62, such as rubber, similar to that used on a platen and is secured in the usual manner to a shaft 63, journalled in bearings 64 secured to the feed table 50 by screws 54. These bearings 64, as shown in Fig. 8, serve to maintain the shape of the tubular portion 51 of the feed table, the latter being secured thereto by screws 53.

The take-up roll shaft 63 is driven from the gear 106 of the feed roll shaft 102. As illustrated in Fig. 8, the shaft 63 extends some distance beyond the end of the right-hand bearing member 64, and has rigidly secured to it a clutch member 65, carrying a pin 66, upon which a series of discs 67, rotatably encircling a sleeve 68, are mounted for axial movement relative to the shaft and sleeve. These discs are interleaved with discs of a second set of discs 69, which are keyed to the sleeve as indicated at 120, Fig. 8. A second sleeve 121, slidably mounted on the first sleeve, is normally engaged by a compression spring 122, and maintained in engagement with the endmost disc retaining the discs 67 and 69 in frictional contact with each other, whereby a driving connection is normally maintained between the shaft 63, upon which the sleeve is rotatably journalled, and an aligned stub shaft 124 to which the sleeve is pinned, as indicated at 125.

The stub-shaft 124 is journalled in the bracket 86 and is provided with a driving gear 126, constantly meshing with an idler gear 127 mounted on a stud 128 carried by the bracket 86 in the usual manner. The idler gear meshes with the 45 gear 106 of the feed roll shaft 102, thereby driving the roll 60 periodically in timed relationship with the feed roll 70.

Inasmuch as I contemplate the wrapping of the worksheet several times about the periphery of 50 the roll, an adjustment is provided, in which the driving connection between the discs may be regulated, so as to permit a certain amount of slippage to prevent the winding of the worksheet from interfering with the progression thereof by the 55 feed rolls 70 and 71. As shown, this adjustment comprises a nut 129, threadingly carried by the sleeve 68 and arranged to increase or decrease the pressure of the compression spring 122 as desired, to the end that the rotation of the roller 60 serves only to wind the sheet and retain it taut.

The worksheet W is maintained in contact with the take-up roll 60 by suitable rollers 61, heretofore mentioned. These rollers are best illustrated in Figs. 9 and 10. As there shown, I provide three 65 roller units, each of which comprises four rollers 61, carried in pairs, one pair arranged to engage the take-up roll 60 from one side, and the other pair from a substantially diametrically opposite side.

70 Each pair of rollers 61 is mounted on a rod 131. These rods are individually mounted for movement toward the axis of the roll 50, in respective slots formed in ears 132, punched outwardly from the tubular portion 51 of the feed plate 50. As 75

shown in Fig. 9, the rollers 61 of each pair are spaced apart from each other on its supporting rod, and the rod therebetween is engaged by one end of a spring 133, the other end of which, as 5 at 134, engages the rod of the diametrically opposite roller. The spring 133 maintains the rollers in contact with the roll 60, or the sheet wrapped therearound, the rollers 61 extending, as illustrated in Fig. 9, through the slots in the tubular 10 housing 51 resulting from the forming of the ears 132.

When it is desired to withdraw a worksheet from the machine, the rollers 70 and 71 are separated, and the roll 60 is disconnected from its 15 driving mechanism. The rollers 70 and 71 are separated for this purpose by swinging of the lever 113 clockwise (Fig. 5). This movement of the lever 113 also disconnects the driving connection between the take-up roll shaft 63 and its 20 driving shaft 124, whereupon the roll is free to be rotated, thus permitting the unrestricted withdrawal of the sheet from the tube 51.

As indicated in Figs. 5 and 6, the hub of the 25 lever 113 is provided with a cam surface 140, arranged to engage one end of a lever 141, pivoted intermediate its ends to the bracket 86, as shown in Fig. 1, at 142. The other end of this lever is provided with a yoke formation embracing the sleeve 121. The arms 143 of this yoke are 30 provided with suitable pins 144 which engage the walls of an annular recess 145 in the sleeve 121, so that consequent upon the swinging of the lever 113 to separate the feed rolls 70 and 71, the sleeve 121 will be moved toward the right (Fig. 8) 35 against the action of the spring 122, relieving the pressure between the discs 67 and 69.

The feed table or plate 50 is secured to the bracket 86 in any well-known manner, such as, for instance, by screws extending through openings 55 in the plate and engaging the brackets. 40 Hence, the feed table and bracket may be removably secured as a unit to the printing machine. As shown, the feed table and bracket 86 are provided on their undersurfaces with a plurality of forked attaching clips 150, arranged to engage the heads of suitable studs 151, which are mounted for vertical movement in the frame 10 of the printing mechanism and normally maintained in their lowermost positions by compression springs 152. Thus, the lister, comprising the feed table 50 and its operating mechanism, may be readily slid into position on the printing machine. The lister unit is secured in position on the printing machine by a rod 156, the lower end 55 of which is provided with suitable threads 157 arranged to engage a frame boss 10a of the printing machine. If desired, a locating pin, such as indicated at 158, in Fig. 5, may be secured to either the printing machine frame 10, or the lister bracket 86, and engage suitable location openings in the other member.

As heretofore mentioned, the printing operation is carried out through the medium of a ribbon R, which lies between the printing device D 65 and the worksheet W. To protect the worksheet from the printing device, I prefer to cover as much as possible of the ribbon R with a comparatively thin metal sheet or guard 169 which has a cut-out portion 161 of sufficient size to permit the exposure of only that portion of the ribbon lying immediately above the printing characters of the printing device.

The guard 169, as shown in Figs. 9 and 10, is considerably thinner than the feed table 50, and is secured thereto by suitable pins 162 arranged

to engage suitable recesses or notches 163 formed in an undercut portion of the plate 50. The plate 50 is provided with an opening 165, through which the feed rollers 70 and 71 extend.

To align the sheet on the guide table 50, I 5 prefer to provide the lister with a pair of guides 166. These guides each comprise an angular shaped member having one leg 167 in engagement with the surface of the feed table 50 and an upstanding leg 168 to guide the edge of the 10 sheet for movement in a direction parallel with the printing device guideway 11.

The guides 166 may be rigidly secured to the ends of rods 169 which are slidably mounted in brackets 170 or 171. These brackets are carried 15 by the feed table 50 and the bracket 86 respectively. Set screws 172 are mounted in the usual manner in the brackets 170 and 171 to retain the guides 166 in an adjusted position to accommodate sheets of various widths, as well as to enable 20 multi-columnar lists to be readily made.

I claim:

1. In a listing mechanism, the combination for means for making successive impressions on a detached sheet, means to advance the sheet once 25 for each impression made thereon, and a roller and gripping means associated therewith to receive the impressed sheet and roll it up.

2. In a listing mechanism, the combination of means for making successive impressions on a 30 sheet, means to feed the sheet after each impression is made, a roller adapted to receive the impressed sheet and roll it up and having its axis extending in a direction transverse to the direction of feed, and means to retain the im- 35 pressed sheet in contact with the roller.

3. In a listing mechanism, the combination with means for making successive impressions on a sheet, means to advance the sheet for each impression, a tubular member to receive the im- 40 pressed sheet, and movable rolling mechanism within the tubular member adapted automatically to roll up an individual sheet received by said member.

4. In a listing mechanism, the combination of 45 means for making successive impressions on a sheet, means for feeding the sheet after each impression made thereon, a tubular member, a roller within said tubular member, means to guide the impressed sheet into the member and into 50 contact with said roller, means carried by the tubular member to maintain the sheet in contact with said roller, and means to rotate said roller.

5. In a listing mechanism, the combination with means for making successive impressions on a 55 worksheet, means to advance the sheet for each impression made, a tubular member, a roller within 60 said member, the periphery of said roller being spaced from the internal wall of the member, said feeding means adapted to advance the sheet into said member, and means to rotate said roller and thereby wind the sheet about the periphery of the roller within said tubular member, and means to maintain the sheet in contact with said roller.

6. In a listing mechanism, the combination with means for making a series of impressions on the worksheet, a roll around which an impressed sheet may be wound, feeding means to feed a sheet for each impression made, means to guide the forward edge of the impressed sheet into gripping contact with said roll, and means whereby said sheet may be wound about said roll consequent upon the operation of said feeding means.

7. In a listing mechanism, the combination with means for making successive impressions on the worksheet, means for feeding the sheet once for each impression, and means independent of the feeding means to grip the forward end of the impressed sheet automatically and roll it up. 5
8. In a printing machine, the combination, with means for making successive impressions from successive printing devices of a series, of means to feed a worksheet, once for each impression made, means to grip the forward end of the impressed sheet and roll the sheet up, and means to guide the sheet from the feeding means to the gripping means. 10
15. 9. In a listing mechanism, the combination of means for making successive impressions on a worksheet, a pair of rolls adapted to grip and periodically feed the sheet for each impression made, a roller, means to guide the forward edge of the impressed sheet toward said roller, means to rotate said roller, and means to cause the forward edge of said sheet to engage the roller and the sheet to be wound thereabout consequent upon the operation of said feeding rolls. 20
25. 10. In a listing mechanism, the combination of means for making impressions successively from each of a series of printing devices, a pair of rolls adapted to grip and periodically feed the sheet between each impression, a planular work 30 supporting table member terminating in a tube, whereby an impressed sheet fed along said table may be coiled in said tube, means carried by the tube to coil the impressed sheet.
11. In a listing mechanism, the combination of means to make successive impressions on the sheet, means to feed the sheet forwardly for each impression made, a table to support said worksheet while the impression is being made, said table having its forward wall extending upwardly, then forwardly, then downwardly, thereby forming a tubular portion extending above the plane of the feed table, and means to roll the sheet up in the tubular portion of said table. 40
12. In a listing mechanism, the combination with means for making successive impressions on a worksheet, a tubular member having a plurality of openings therein, a roller within said member, the periphery of said roller being spaced apart from the internal wall of the member, feeding means adapted to advance the impressed sheet into said member, and means to rotate said roller and thereby wind the sheet about the periphery of the roller, and means including rolls carried by said member and entering the openings therein to maintain the sheet in contact with said roller. 50
13. In a listing mechanism, the combination of means for making successive impressions on a sheet, means for feeding the sheet after each impression made thereon, a tube having an axially extending entrance opening, a roller within said tube, guides on the exterior of the tube, axles slidably mounted in the guides, rolls on the axles extending through openings in the tube into engagement with the roller, and arcuate springs extending about the tube and bearing on said axles to press them toward the roller. 60
14. In a printing machine, the combination with the guideway along which printing devices may be fed one at a time, a platen, a platen-supporting member extending upwardly from and forwardly above said guideway, the forwardly extending portion of said member being above the guideway, a platen carried adjacent the forward end of said member and means to cause the platen to periodically make impressions from the printing devices in said guideway, means to feed a sheet after each impression, and means permanently disposed between the upwardly extending portion of said platen supporting member and said platen to receive and roll up the impressed sheet. 5
15. In a printing mechanism, the combination with a frame having a guideway, of means to feed printing devices one at a time along said guideway, a pair of platen-supporting members extending upwardly from said guideway adjacent one end thereof and having forwardly extending arms parallel with and spaced above said guideway at opposite sides thereof, a platen carried adjacent the forward ends of said arms and extending downwardly therefrom, said platen being arranged to periodically coat with printing devices on said guideway to make impressions therefrom, a sheet-feeding mechanism including means to feed a sheet after each impression, an elongated tubular member extending in a direction transverse to said guideway, beneath said overhanging arms and in a region between the vertical portions of the supporting members and the platen and above said guideway, and means to guide the impressed sheet into said tube. 10
16. In a printing machine, the combination with a guideway, of means to periodically feed a series of printing devices one at a time along said guideway, a platen, a platen supporting arm extending upwardly from and forwardly above the guideway, the forwardly extending portion of said arm being spaced above said guideway, a platen carried adjacent the forward end of said arm, means to periodically cause the platen to make impressions from each printing device as it reaches a predetermined position in said guideway, a sheet-feeding mechanism, an elongated tubular member having an elongated entrance opening and positioned between the platen and the upwardly extending portion of said arm and between the forwardly extending portion of said arm and the guideway, means to feed the sheet toward said tubular member after such impression, a roller mounted within said tubular member and having its axis extending in a direction parallel with the axis of the tubular member, and means to retain the sheet received by said tubular member in contact with the periphery of the roller, and means to rotate the roller whereby a sheet may be wound in said member between its inner wall and the roller. 45
17. In a listing mechanism, the combination with power-operated means for making successive impressions on a sheet as distinguished from a web, power-operated means for feeding the sheet for each impression, and means to receive the impressed sheet, and power operated means associated with said receiving means to roll up the sheet automatically. 50
18. In a listing mechanism, the combination of means for making successive impressions on a sheet, means for feeding the sheet after each impression made thereon, a tube, and power-actuated means to automatically roll the impressed sheet in said tube consequent upon the operation of said feeding means. 65
19. In a listing mechanism, the combination of means for making successive impressions on a sheet, means for feeding a sheet after each impression, a tubular member and power-actuated means to make the sheet go round and around in the tubular member, and means to 70
- 75

permit the sheet to be drawn in the reverse direction out of said member.

20. In a mechanism, the combination of means for making successive impressions on a sheet, means to advance the sheet for each impression, a tubular member, power-actuated means supported within the tubular member to grip the sheet and cause it to be rolled therein, and means to permit the unwinding of said sheet from the 10 tubular member.

21. A sheet handling mechanism for an addressing machine having means for making successive impressions on a sheet, said mechanism comprising intermittently acting means to advance a sheet a predetermined distance following each impression, means to receive and automatically grip the foremost edge of an impressed sheet and roll it up, means to actuate said rolling means consequent upon the operation 20 of said advancing means.

22. A sheet handling mechanism for a power-operated addressing machine having means for making successive impressions on a worksheet, said mechanism comprising a power operated feeding means arranged and adapted to feed a sheet a predetermined distance at a predetermined lineal speed following each impression, a roller, means to guide the impressed sheet into contact with said roller, means to maintain said impressed sheet in contact with said roller, and means frictionally connecting the roller with a moving part of the addressing machine to rotate the roller to move its periphery at a greater rate of speed than the lineal speed of said sheet, 30 due to the action of said feeding means, and means to permit the sheet to be unwound from said roller.

23. A sheet-feeding mechanism comprising a planular sheet supporting table having the forward end thereof gradually merging into a tube formation, a pair of separable feed rolls mounted on said table and arranged and adapted to grip a sheet, means to periodically rotate said rolls to feed the gripped sheet forward a predetermined distance, a roller axially mounted in said tube and having its periphery spaced apart from the internal walls of said tube, rolls supported by said tube and projecting through openings in the tube, resilient means to urge said last-named rolls into contact with the roller, means to intermittently rotate said roller consequent upon the operation of said feeding means 40

to cause the periphery of said roller to travel a greater distance than the distance the feed rolls advance the sheet, friction driving means interposed between the last-named means and said roller whereby that portion of the sheet between 5 the feed rolls and the roller is maintained in tension, and means to separate said feed rolls and disconnect the driving means from said roller to enable the sheet to be manually unwound from said tube and drawn rearwardly 10 across said table.

24. In a listing mechanism, the combination of means for making successive impressions on an individual sheet, a slotted tubular member containing a wind-up mechanism, means for feeding the impressed sheet into the tubular member, and means for attaching the sheet to the wind-up mechanism by the mere act of feeding it into the tubular member.

25. In a listing mechanism, the combination 20 of means for making successive impressions on a detached sheet, means to automatically grip the sheet and wind it up following the impressions, and a slotted tube substantially surrounding the wound up sheet.

26. In a listing mechanism, the combination of means for making successive impressions on a detached sheet, means to feed the sheet a definite amount for each impression, independent wind up mechanism adapted to grip the sheet, 30 and mechanism enabling it to maintain the sheet wound up at a rate caused by the feeding mechanism.

27. The combination of means for making successive impressions on a detached sheet, a roller 35 and gripping means adapted to automatically receive the end portion of the impressed sheet, and a friction drive for the roller whereby the sheet is wound up about the roller.

28. A listing mechanism, the combination of 40 means for making successive impressions on a work sheet, a substantially tubular member having a slot into which the sheet may pass, a pair of feed rollers to engage the sheet and feed it a definite distance for each impression, into the 45 tubular member, a winding roller within the tubular member, a gripping roller extending through an opening in the tubular member into engagement with the winding roller, and a friction drive for the winding roller.
